(57) **CLAIM**

The ornamental design for a doll, as shown and described.

DESCRIPTION

FIG. 1 is a front view of a doll showing my new design;

FIG. 2 is a rear view thereof;

FIG. 3 is a side view thereof;

FIG. 4 is an opposite side view of the doll with the hand and
arm shown in a different position;

FIG. 5 is a top plan view of FIG. 1; and,

FIG. 6 is a bottom plan view of the doll with the hands and
flag shown in different positions.

The broken lines shown on the claimed design represent
stitching.
